United States Patent

Des. 239,071

Patented Mar. 9, 1976

239,071

COMBINATION CABINET AND STAND

Arthur Robson, Jericho, N.Y., assignor to Morse
Electro Products Corp., Brooklyn, N.Y.

Filed Nov. 4, 1974, Ser. No. 520,375

Term of patent 14 years

Int. Cl. D6—04

U.S. Cl. D6—27

FIG. 1

FIG. 3

FIG. 2

FIG. 4

FIG. 1 is a perspective view of a combination cabinet and stand showing my new design;

FIG. 2 is a front view thereof;

FIG. 3 is a rear view thereof; and

FIG. 4 is a side view thereof, the other side view being substantially identical.

I claim:

The ornamental design for a combination cabinet and stand, as shown and described.
